US00D942965S

(12) **United States Design Patent** (10) Patent No.: **US D942,965 S**
 Kim et al. (45) Date of Patent: **** Feb. 8, 2022**

(54) **SOUND BAR**

(71) Applicant: **LG ELECTRONICS INC.**, Seoul (KR)
 (72) Inventors: **Yongseok Kim**, Seoul (KR); **Yooseok Kim**, Seoul (KR); **Minji Seo**, Seoul (KR)
 (73) Assignee: **LG ELECTRONICS INC.**, Seoul (KR)

(**) Term: **15 Years**

(21) Appl. No.: **35/510,323**

(22) Filed: **Mar. 5, 2020**

(80) **Hague Agreement Data**

Int. Filing Date: **Mar. 5, 2020**

Int. Reg. No.: **DM/207092**

Int. Reg. Date: **Mar. 5, 2020**

Int. Reg. Pub. Date: **Sep. 18, 2020**

(30) **Foreign Application Priority Data**

Sep. 19, 2019 (KR) 30-2019-0044968

(51) **LOC (13) Cl.** **14-01**

(52) **U.S. Cl.**

USPC **D14/214**; D14/215

(58) **Field of Classification Search**

USPC D14/125–129, 131, 132, 170–172, 209.1, D14/210, 211, 214, 215, 217, 239, 336,

D14/341, 373–377

CPC G06F 1/1601; G06F 1/1605; G06F 1/162
